UNITED STATES PATENT OFFICE.

VICTOR BÉLANGER, OF MARSHFIELD, MASSACHUSETTS, ASSIGNOR TO NEW ERA SPINNING CO., OF BOSTON, MASSACHUSETTS, A CORPORATION OF MASSACHUSETTS.

DEVICE FOR SPINNING AND TWISTING TEXTILE FIBERS.

1,230,097.

Specification of Letters Patent. Patented June 19, 1917.

Application filed April 7, 1911, Serial No. 619,476.

Renewed November 6, 1916. Serial No. 129,894.

To all whom it may concern:

Be it known that I, VICTOR BÉLANGER, citizen of the United States, and resident of Marshfield, Massachusetts, county of Plymouth, have invented certain new and useful Improvements in Devices for Spinning and Twisting Textile Fibers, of which the following is a specification.

This invention relates to the art of spinning and is an improvement upon the type of spinning machine shown and described in my earlier co-pending application Serial Number 595,187. The present improvement is intended to render more easy and certain 10 the action of the rotary yarn-engaging device which co-operates with the spindle member by providing a novel form of connection between these two members and further by providing an improved form of cap-supporting or lifting device in order to more effectively control the action of said cap or 15 yarn engaging member.

Another improvement set forth herein has relation to the adjustment by which the 20 relations of the controller and the rotary cap are adjusted in order to regulate the tension. Another feature of the present invention consists in providing an extensible portion 25 for the spindle member adapted to permit the cap to be raised so as to build the cap the full length of the spindle member or bobbin.

These and other features of the invention 30 will be more particularly explained in detail with the aid of the accompanying drawings 35 of which—

Figure 1 is a side elevation partly in central section showing the relations of principal parts.

Fig. 2 is a central sectional view in elevation of the improved lifting member.

Fig. 3 is a cross sectional view thereof.

Figs. 4 and 5 are detail sections of the cap and its intermediate coupling member.

Figs. 6 and 7 are respectively plan and 45 side views of the means for adjusting the lifting member vertically with relation to the rail or to the edge of the controller.

Fig. 8 is an elevation partly in central section showing the relation of the parts and 50 of the controller adjusting means.

Figs. 9, 10, 11 and 12 are detail views illustrating the construction of the extensible bobbin and means for locking the exten-

sion member to the bobbin proper and to the cap.

Figs. 13, 14 and 15 are views in detail of modified forms of construction by which the extension member is connected with the cap.

As in my former specification I will use the term spindle member as applicable either 60 to the cop tube or bobbin when the yarn is wound upon a detachable bobbin or to the spindle itself when the yarn is wound on the bare spindle without the intervention of a cop tube, although in general practice the 65 former is far more usual.

In the practice of my invention according to the form illustrated in the drawings, I employ the rotary spindle member *a* and a cap *b* which may be of any suitable shape 70 adapting it to be connected to the spindle member at one end by means of a sliding engagement or connection, its other end being formed with a smooth yarn engaging edge which serves by its engagement with the 75 yarn to assist the revolution of the yarn about the axis of rotation while allowing the yarn to lag or slip, in order to cause it to wind upon the spindle-member.

To secure the proper engagement between 80 the spindle-member and the yarn engaging member or cap, I employ an intermediate coupling member or clutch member *b'*, which is so to speak, insulated for the most part from the adjacent portion of the cap by 85 means of any suitable shock or vibration absorbing device. This shock absorbing device is intended to prevent the transmission of vibration between the spindle and the cap, and it may consist simply of an annular 90 band or tubular piece *b²*, of yielding material such as textile or other fibrous material, rubber or the like, or a piece of spring metal. The clutch *b'* is centrally bored to fit around the spindle with a slight degree of play or 95 looseness and should have such locking engagement with the spindle member as will cause it to rotate in unison with the spindle, this being effected in this instance by means of a key *b³* fitting into one or more keyways 100 or grooves *a'* extending lengthwise of the spindle member. The clutch is prevented from turning in relation to the cap by means of the stud or screw *b⁴* which projects from the outside of the clutch through a corresponding hole or opening in the cap.

The lifting or cap supporting member in this case is shown as a wheel c mounted in an anti-friction bearing and having one annular supporting face c^2 adapted to project beneath the overhanging edge of the cap b to give vertical or axial support to the cap and having another bearing surface c' which affords lateral support or engagement with the said cap in order to steady it against lateral vibration. It is the function of this pivot wheel both to sustain the cap vertically and to keep the cap disengaged from centrifugally clutching the spindle, so as to permit a free axial movement without binding between the cap and the spindle member. I prefer to overhang slightly the lateral face c' of the pivot wheel and also to give the bearing face c^2 of the wheel a slight bevel or inclination.

I also prefer to mount the pivot wheel so as to give it a slight yielding pressure laterally against the cap, and the construction by which this is accomplished according to the form illustrated in the drawings is as follows:

The wheel c is carried by a shaft c^4 with a conical foot which is supported in a bushing c^5 in which are perforations near the top and the bottom and whose periphery is fluted to form vertical channels for the flow of oil. The bushing c^5 is supported in an oil tube c^6 in the bottom of which is an elastic cushion c^7 . The oil tube c^6 is carried in an eccentrically bored holder c^8 , a sleeve c^{30} of fabric being interposed to form an annular cushion around the oil tube. The holder c^8 is carried by a bolster c^9 clamped into the coppering rail d by a nut c^{10} to permit circumferential adjustment of the bolster. The holder c^8 is given a slight torsional pressure by means of a spiral spring c^{12} anchored to a fixed block c^{11} , and having its upper end secured to the holder so that the shaft bearing and the wheel itself are pressed with a light yielding pressure toward the cap b . The bearing portions c' , c^2 of the wheel may be made of any suitable material, but I prefer a relatively soft substance like felt or leather, which may be clamped in place between rigid members or washers. I prefer to construct the wheel so that the upper lateral bearing c^{13} will engage the shaft above the bearing face c^2 for better support.

A controller plate e is mounted on the rail d in position to engage and retard the revolving yarn adjacent to the edge of the cap. The extent of retardation and hence the tension of the yarn will depend upon how far the upper indented edge e' of the controller e projects above the lower edge of the cap. As the vertical position of the cap is determined by the pivot wheel c said adjustment may be effected by adjusting the pivot wheel vertically or by adjusting the controller vertically. In Fig. 1, I have shown the pivot

wheel provided with a vertical adjustment, while in Fig. 8, I have shown the controller provided with the vertical adjustment. In Fig. 1, the controller plate is shown mounted upon a shock absorbing cushion or washer e^2 .

Any suitable form of adjusting device may be employed in the form illustrated in Fig. 1. The oil containing tube c^6 forming part of the bearing support for the pivot wheel is provided at its upper edge with a radial flange c^{20} which is engaged by the inclined raised portion f' of an adjustable strip f which extends the whole length of the rail, the raised portions f' being struck up from the sheet metal as shown in Figs. 6 and 7 in a proper position to pass beneath and engage the flange c^{20} on opposite sides. The metal portion of the strip f is cut away to form an aperture to receive the body of the tube c^6 . Obviously a longitudinal movement of the adjusting bar or strip f will act by reason of the inclined surfaces f' to raise the tube c^6 or to allow it to drop according to the direction of its movement. The bar f is locked in its position of adjustment by means of a suitable device, such as set screws f^3 .

In Fig. 8, I have shown the same form of adjusting strip applied to the controller instead of to the pivot wheel. In this case the controller e is provided with an annular flange e^{21} and is made long enough to extend through the spindle orifice in the rail d , so as to be guided thereby. I also use a spiral compression spring e^3 which serves normally to depress or turn down the controller plate, while allowing it to rise under the action of the adjusting bar or rail f .

Since the yarn can be delivered to the spindle member only from the bottom of the cap, and since the top of the cap must always engage the spindle member, it is obvious that when using an ordinary cop tube on a spindle, the cop tube cannot be filled clear to the top. To obviate this objection I have provided a removable extension member g , which corresponds in cross section to the cop tube or bobbin which it registers with when in position. This extension member g is provided with a downward extension g' of smaller diameter than the cap engaging portion, this smaller part being provided with longitudinal slots which divide it as shown in Figs. 9 and 10 into three spring members or fingers g^2 capable of being compressed toward each other to pass inside the upper end of the cop tube proper, upon which the yarn is wound. Under the influence of centrifugal action when rotating, these spring fingers will expand outward and clutch the inside of the cop tube so as to remain secure thereto during the operation of the machine, while being detachable therefrom by simply pulling them upward.

To prevent the caps and the extension

members from falling apart when removed from the spindle for doffing, I have provided means which serve to interlock these two members together when the cap is raised to 5 the top of the extension member. This retaining means may be of any suitable form, and in Fig. 9 is shown to consist of a tubular cap h of spring metal secured to the top of the extension piece and slotted axially and 10 radially, as shown in Figs. 9 and 12, to make the lower edge of the tube compressible and extensible. Under this lower edge the tube is formed with an annular projecting lip h' adapted to pass inside of and engage the 15 inwardly projecting annular lip b^{20} formed in the clutch member b^{10} . By this means the cap when pushed toward the upper end of the extension member g is automatically but 20 detachably interlocked with the extension piece.

Various other means may be used for effecting this interlocking engagement, such for example, as that shown in Figs. 13 and 25 14, in which the portion of the extensible member forming the bottom of the groove engaged by the key of the cap is severed from the rest of the extension piece g' , so as to 30 form a yielding notched spring lip g^3 adapted to engage and interlock with the key b^3 of the clutch member.

In Figs. 14 and 15, I have shown a split ring i one end of which is turned in to form a projection i' to pass through the upper end of the cap and engage a hole bored in the 35 clutch member b' . This spring is preferably seated in an annular groove formed on the exterior face of the cap, as shown in Figs. 8 and 14.

It will be understood that when the 40 controller or tension device is not in operative position to perform its function of retarding the yarn that the retardation of the yarn will be caused by the "ballooning" of the 45 yarn due to centrifugal action and the resistance of the air. Obviously the ballooning and the resistance will be greatest, other things being equal, when the length of the ballooning yarn is greatest, and will be diminished as the cap approaches the top of 50 the spindle. To equalize the tension on the yarn between the thread-eye and the cap, I employ means for lifting the thread-eye as the cap approaches the top of the spindle. This may be accomplished in a variety of 55 ways but for the purpose of illustrating the principle, I have shown in Fig. 8 the thread-eye m mounted on the vertical shank m' secured to the lifting rail d by means of an adjusting set screw. With the arrangement 60 just described the thread-eye will always be a uniform distance above the bottom of the cap and consequently the length of the ballooning yarn will be the same whether the lifting rail be near the bottom of the cap or 65 at the highest point of its traverse.

While this invention has been shown and described as applied to the art of spinning, it will nevertheless be understood that it is based upon the discovery of the mechanical principle that two concentric bodies rotating 70 at high speed may be prevented from being clutched together by centrifugal action by arranging an independent member so as to engage one of the rotating bodies at a point outside of the axis of rotation, but so as to 75 allow the rotation, and upon the further principle that the interposition of a shock-absorbing device or medium between the two bodies still further facilitates the neutralization of such centrifugal clutching action. 80 The neutralization of this centrifugal engagement is important because it allows one member to move freely axially of the other member, and as this movement is desirable in many mechanical devices besides spinning 85 machines, I do not confine the use of the new combinations herein set forth and claimed to such machines.

What I claim is:

1. In a cap spinning device the combination with a rotary spindle, of a rotary reciprocatory yarn-engaging cap mounted thereon and driven thereby, an external bearing member supporting the cap axially and having lateral bearing engagement with the cap 90 and located to allow the revolving yarn to pass between itself and the cap substantially as described.

2. In a cap spinning device the combination with a rotary spindle, of a rotary reciprocatory yarn-engaging cap mounted thereon and driven thereby, an external rotary bearing member provided with two bearing faces extending substantially perpendicular to each other and affording respectively 100 axial and lateral support for the cap while allowing the revolving yarn to pass between the cap and the bearing member at each revolution.

3. In a cap spinning device the combination with a rotary spindle, of a rotary reciprocatory yarn-engaging cap mounted thereon and driven thereby combined with means for affording both lateral and axial support to said cap while allowing the yarn to revolve around the outside of said cap substantially as described. 110

4. A combination with a rotary spindle of a rotary reciprocatory yarn-engaging cap mounted thereon and driven thereby an external rotary bearing member arranged to afford both axial and lateral support to said cap while allowing the yarn to revolve around the exterior of said cap said bearing member being yieldingly mounted substantially as described. 120

5. In a cap spinning device the combination with a rotary spindle, of a rotary reciprocatory yarn-engaging cap mounted thereon, and driven thereby, an external 130

bearing member formed with two bearing surfaces angularly disposed with relation to each other and affording both lateral and axial support for said cap, the lateral bearing face being formed of yielding material, substantially as described.

6. A traverse member for a cap-spinning frame embracing in its construction, a flanged bearing head comprising, a substantially cylindrical portion adapted to form a lateral bearing against the peripheral surface of the rotating cap, a horizontal projecting flange portion arranged to project beneath the lower end of the cap to support 10 the vertical thrust of the cap, and a central shaft perpendicular to said head, and a bolster forming a footstep bearing for the shaft, substantially as described.

7. A rotary traverse member for a rotary 20 spinning-cap embracing in its construction, a flanged bearing head having two angularly disposed circular bearing faces for engaging respectively the side and the bottom edge of the spinning-cap, a central shaft, a holding member in which said shaft is eccentrically mounted to permit adjustment by rotation of said holding member while maintaining the parallelism of said shaft in its 25 different positions of adjustment, substantially as described.

8. A rotary traverse member for a rotary spinning-cap embracing in its construction, a bearing head having two circular bearing faces at approximately a right angle to each 35 other, a central shaft for rotatably supporting said head, an automatically adjustable bolster forming a bearing for said shaft by which the shaft is adjusted laterally while maintaining its parallelism, substantially as 40 described.

9. A rotary bearing member for a cap-spinning frame embracing in its construction, a bolster, an anti-friction bearing wheel having two circular bearing faces disposed 45 at substantially a right angle to each other to form both vertical and lateral supporting engagement with the cap, a central bearing shaft, a bearing member located within the bolster to support said shaft, and a cushion interposed between the bolster and the bearing member to absorb vibration between the bolster and the shaft, substantially as described.

10. In a cap spinning device the combination 55 of the rotary spindle, a reciprocating hollow cap having engagement with said spindle to rotate therewith and slide thereon, a bearing member adapted to engage the lower edge of said cap to support it laterally and axially, substantially as described.

11. In a cap spinning device the combination 60 of the rotary spindle or shaft, a hollow cap, a connecting bushing secured to the cap and having sliding engagement with the spindle, and a vibration absorbing device

for minimizing the transmission of vibration from the bushing to the cap, substantially as described.

12. In a cap spinning device the combination 70 of a rotary shaft or spindle, a hollow cap, means for connecting said spindle and said cap to impart rotation from the spindle to the cap while allowing one of said elements to have axial movement relative to the other, said connecting means embracing a 75 vibration absorbing device to lessen the transmission of vibration from one element to the other, substantially as described.

13. In a cap spinning device, the combination 80 with a rotary yarn-engaging cap member and its central and supporting driving spindle, of a bushing member or sleeve centrally located inside the cap to permit a slight rocking motion of the cap in relation thereto and means for opposing a yielding 85 or resilient resistance to said rocking movement substantially as described.

14. The combination of the hollow cap, 90 a bushing mounted therein, a spring member for holding said cap and bushing from separation, an elastic cushion interposed between the bushing and the cap to absorb vibration, substantially as described.

15. In a spinning machine the combination 95 with a rotary spindle member, a yarn-engaging cap whose lower edge engages the revolving yarn as it passes to the spindle, said cap having sliding engagement with said spindle, an anti-friction bearing member 100 engaging the edge of the cap, and a controller device adapted to project above the lower edge of the cap, and means for vertically adjusting the controller member varied to regulate the tension of the yarn, substantially as described.

16. In a spinning machine the combination 105 of a series of rotary spindles, the hollow spinning caps mounted thereon to rotate therewith, a supporting rail, a series of bearing members carried by said rail to engage the edges of the respective caps, controller devices whose edges are arranged to project beyond the edges of their respective caps to engage and retard the yarn and an adjusting device mounted on the rail for simultaneously varying the relative position of the caps and the controllers in order to vary the tension of the yarn, substantially as described.

17. The combination of the rotary spindle 120 member or shaft, a hollow yarn-engaging cap, a centrally disposed member adapted to form an extension of the spindle member and formed to detachably engage said spindle member, said extension member being 125 provided with means for detachably locking the cap to itself, substantially as described.

18. The combination of a hollow bobbin, 130 an extension member whose lower end terminates in spring fingers adapted to engage

- the upper end of the bobbin internally the 45
yarn-engaging cap having sliding engagement
with said extension member, and means
for detachably locking the cap to the
5 tension member, substantially as described.
19. The combination of the yarn-engag- 50
ing cap, an extension bobbin member located
within the said cap and splined thereto, and
means for detachably interlocking the ex-
10 tension member and the cap together, sub-
stantially as described.
20. A rotary traverse member for a spin- 55
ning-cap embracing in its construction, a
central shaft or spindle, a bearing head se-
15 cured thereto and adapted to engage and
support a spinning-cap, said head having a
disk of yielding material forming a lateral
bearing face in order to lessen vibration be-
tween the traverse member and its cap, sub-
20 stantially as described.
21. The rotary spindle member, the rotary 60
cap mounted thereon to have sliding engage-
ment therewith, a supporting wheel ar-
ranged to laterally engage said bearing cap,
25 the bearing portion of said wheel being made
of yielding material between which and the
cap the revolving yarn passes at each revolution,
substantially as described.
22. The combination with the rotary 65
30 spindle, a rotary reciprocating hollow cap
mounted thereon and rotated thereby, a
rotary bearing member forming an ex-
ternal support for said cap, a traverse
35 rail, an annular yarn-engaging member for
partially retarding the revolution of the
yarn, and means movably mounted on said
rail to engage said retarding member for
vertical adjustment in order to vary the
40 tension on the yarn, substantially as de-
scribed.
23. The combination of a rotary shaft, 70
a hollow yarn-engaging rotary cap, means
for forming a cushioned connection be-
tween the shaft and the cap, a yarn-retard-
ing device arranged to engage the revolv- 75
ing yarn adjacent to the yarn-engaging
edge of the cap said yarn-retarding device
being adjustable axially in relation to the
edge of the cap, substantially as described.
24. The combination of the rotary shaft 80
or spindle, a rotary cap mounted thereon
to rotate therewith and having sliding en-
gagement with said spindle, a retarding de-
vice arranged adjacent to the yarn-engag- 85
ing edge of the cap said retarding device
being adjustable in order to vary the ten-
sion on the yarn, substantially as de-
scribed.
25. A cap for a cap-spinning frame embrac- 90
ing in combination, a hollow cup-like 60
member or cap, a tubular bushing or sleeve
located therein and formed to have a slid-
ing splined engagement with the central
spindle member, the sleeve and the cap
being interlocked to rotate and reciprocate 65
in unison, a yielding or resilient cushion
member arranged to oppose a yielding re-
sistance to the angular movements of the
cap in relation to the sleeve, substantially
70 as described.
26. A spinning cap for a cap-spinning 75
frame embracing in combination, a hollow
shell, an internal tubular member with
which said shell has a splined engagement
to permit the reciprocation of the shell 80
axially of said tubular member, said tubu-
lar member being constructed to engage the
supporting bobbin and to form an upward
extension to said bobbin whereby the cap
may be given a traverse movement above 85
the upper end of the bobbin-member, sub-
stantially as described.

In witness whereof, I have subscribed
the above specification.

VICTOR BÉLANGER.
